UNITED STATES PATENT OFFICE.

EDMUND A. CURTIS, OF CHICAGO, ILLINOIS.

DESIGN FOR A CAR-TRUCK FRAME.

SPECIFICATION forming part of Design No. 32,929, dated July 10, 1900.

Application filed June 7, 1900. Serial No. 19,474. Term of patent 14 years.

To all whom it may concern:

Be it known that I, EDMUND A. CURTIS, a citizen of the United States, residing at Chicago, in the county of Cook and State of Illinois, have invented and produced a new and original Design for Car-Truck Frames, of which the following is a specification, reference being had to the accompanying drawings, in which—

- o Figure 1 is a side elevation of a car-truck frame embodying my design, and Fig. 2 is a plan view of the same.

The novel feature of my design consists in the configuration of the truck-frame, the same being composed of two parallel side members 1, each comprising a top portion 2 and a lower portion 3, which are parallel for the greater portion of their length, their forward ends being curved toward each other, as indicated at 4, and being there united to each other and connected with the corresponding parts of

the other side member by a transverse member 5, the body of which is arranged at right angles to the side members, while its ends are inclined to their junction with the side members. The lower portion of each side member has near its forward end an arch-shaped portion 6, which extends upward at each side of the upper portion of said side member, while the rear portion of the lower part terminates in an arch 7, which extends below the body of the frame at its lower end, while its upper portion is lengthened or extended upward to embrace the rear extremity of the upper part of the side member. 30 35

I claim—

The design for a car-truck frame substantially as shown and described

EDMUND A. CURTIS.
